ATHLETIC PROTECTOR

Forrest M. Record, Beverly Hills, Calif., assignor
of one-half to Gordon Travers, Los Angeles,
Calif.

Application March 6, 1931, Serial No. 520,513

7 Claims. (Cl. 128—158)

This invention relates to athletic supporters, and has for an object the provision of a device of this general character, which serves not only as a supporter, but also as a protective shield whereby the wearer may be protected from injury to the parts of his body covered by the shield.

Another object is to provide an athletic supporter and protecting device as described, which is so designed that it serves to protect not only the external reproductive organs, but also the surrounding area of the groin and lower abdominal regions.

A more detailed object is to provide an athletic supporter and protector composed of a rigid body portion formed in the necessary shape to provide a protective and supporting cup, this body portion being covered with a relatively thick padding material, such as sponge rubber, whereby the wearer is amply protected against injury by being struck.

A still further object is to provide an athletic supporter and protector as described, which is provided with novel means for securing a belt thereto, this belt being employed to retain the device in operative position.

The invention possesses other objects and advantageous features, some of which, with those enumerated, will be set forth in the following description of the invention's particular embodiment which is illustrated in the drawing accompanying and forming a part of the specification.

Referring to the drawing:

Fig. 1 is a view in front elevation of a supporter embodying the principles of the present invention. In this view a portion of the protective covering is broken away to show the internal construction of the device.

Fig. 2 is a side elevation, the direction of view being indicated by the arrow 2 of Fig. 1.

Fig. 3 is an inside elevation of the protective cup and its associated flange. This view may be considered as a vertical sectional view taken upon the line 3—3 of Fig. 2, with the direction of view as indicated.

Fig. 4 is a vertical sectional view taken upon the line 4—4 of Fig. 1, with the direction of view as indicated.

Fig. 5 is a perspective view showing the rigid body portion of the supporter.

Fig. 6 is a horizontal sectional view taken upon the line 6—6 of Fig. 5, with the direction of view as indicated.

Fig. 7 is a fragmentary view of the back portion of the belt, the direction of view being indicated by the arrow 7 of Fig. 2.

The supporter of my invention is intended to be used by male athletes as a supporting and protective device whereby the athlete is efficiently protected against injury when pursuing such sports as boxing, football, and the like. 69 The supporter comprises a rigid body portion, indicated in its entirety at 11, and best shown upon Figs. 5 and 6. This body portion 11 is preferably constructed of aluminum of suitable thickness, because this material is possessed of sufficient 65 inherent strength, and yet is light enough to avoid hampering the movements of the athlete. However, I wish it to be understood that other materials may be substituted for aluminum, such, for example, as sheet fiber of suitable thickness. 70

The body portion 11 is shaped to define a protective cup 12 at the lower portion thereof, and a flange 13 extending upwards from the upper edge of the cup 12. A plurality of apertures are formed in the body portion 11, the apertures 14 75 in the cup 12 being preferably relatively large as compared with the apertures 16 in the flange 13. The flange 13 is preferably perfectly flat when measured in a vertical line, but is arcuate when viewed from above or below, so as to permit it 80 to conform to the general configuration of the lower abdominal region and groins of the wearer. Moreover, this flange 13 is of material extent, so that a relatively large area of the wearer's body is covered thereby. 85

The body portion 11 is provided with a covering 17 of extremely soft, pliant cushioning material, preferably sponge rubber. This cushioning material substantially completely encloses the flange 13, and is relatively thick upon the 90 inner face of the flange 13, as indicated at 18, inasmuch as it is intended that this portion of the covering serve as cushioning means whereby shock imparted to the supporter will be absorbed so as to protect the wearer against 95 injury.

The covering material 17 extends downwards on the outer face of the cup 12, and covers the entire outer surface thereof, as indicated at 19. Moreover, the covering material 17 extends around 100 the lateral and lower peripheral edges of the cup 12, and for a short distance into the interior thereof along its inner face, as indicated at 21, thus providing cushioning material which is interposed between the entire peripheral edge of 105 the cup 12 and the wearer's body. Preferably, these portions of the peripheral edge of the cup 12 are formed T-shaped, having flanges 22 embedded within the cushioning material 17 so as to increase the area of contact of the device 110

with the wearer's body. The cushioning material 17 is retained in position upon the body portion 11, because of the fact that the apertures 16 in the flange 13, and the lower apertures 14 in the cup 12, are filled with the covering material; and in the event this covering material is of sponge rubber, it is vulcanized thereon, so that those portions of the covering material which engage the front and back faces of the body portion 11 are permanently anchored together. By leaving the upper apertures 14 in the cup 12 open, i. e., by extending these apertures through the covering material, as indicated at 23, ample ventilation is provided for the interior of the cup.

A belt 26 is provided, whereby the supporter may be worn comfortably and yet securely, by an athlete. This belt comprises a front portion 27 in the form of a strip of preferably inelastic webbing embedded and preferably vulcanized within the portion 18 of the covering material 17 which extends across the inner face of the flange 13. The ends 28 of the strip 27 project beyond the ends of the flange 13, so as to permit 25 attaching a band 29 to each of the projecting ends, stitching 31 or other suitable attaching means being employed for this purpose. Each of the bands preferably is constructed of resilient material such as elastic webbing, and means are provided for releasably attaching the ends of the bands 29 together. For example, each band is provided with a preferably leather extension 32 at its after end, and alined eyes 33 are provided in each of the two extensions 32, whereby lacing 34 may be employed to releasably secure the two bands 29 together at the wearer's back. Leg strips 36 and 37 also are employed, preferably these leg strips being also of resilient material such as elastic webbing. Each of the leg strips is secured at one end to the belt 26 at the back and at one side thereof, and the other ends of the two leg strips 36, 37 are both secured to the lower edge of the cup 12 by means of preferably a single rivet 38, as best shown upon Fig. 4. Thus, it is readily understood that the two leg strips 36 and 37 cooperate with the belt 26 in holding the supporter in operative position, inasmuch as both leg strips extend downwards from the back portion of the belt 26 through the wearer's crotch and to the lower portion of the cup 12.

Owing to the thickness of the padding material 17 which is interposed between the rigid plate 11, and also owing to the relatively large area of contact of the padding material with the wearer's body, relatively hard blows can be taken on the device of my invention, without subjecting the wearer to injury or even to material discomfort. Furthermore, owing to the details of construction, and the materials employed, the article is capable of being easily kept in a sanitary condition, because it may very easily be washed and dried. Furthermore, owing to the extreme lightness of the entire device which results from the fact that its main body portion 11 is constructed of relatively light but strong material such as aluminum or sheet fiber, the device does not subject the wearer to discomfort, or interfere with his normal movements, even though it is capable of operating efficiently as a supporter and as a protective device for him.

It is to be understood that the details of the invention as herein disclosed, are subject to alteration within the spirit or scope of the appended claims.

I claim:

1. In an athletic protector, a rigid body defining a protective cup and having an integral flange extending upwards and laterally from the upper edge thereof, and a covering of sponge rubber substantially completely enclosing said flange and covering the entire outer surface of said cup, said covering also extending around the lateral and lower peripheral edges of said cup. 80

2. In an athletic protector, a rigid body defining a protective cup and having an integral flange extending upwards and laterally from the upper edge thereof, a soft rubber covering substantially completely enclosing said flange and covering the entire outer face of said cup and extending around the lateral and lower edges thereof, and a belt adapted to encircle the wearer's waist, the front portion of said belt being embedded within the covering of said flange. 85

3. In an athletic protector, a rigid body defining a protective cup and having an integral flange extending upwards and laterally from the upper edge thereof, a soft rubber covering substantially completely enclosing said flange and covering the entire outer face of said cup and extending around the lateral and lower edges thereof, and a belt adapted to encircle the wearer's waist, said belt comprising a strip embedded within the covering on said flange and having its ends projecting beyond the ends thereof, bands secured to said projecting ends, and means for attaching said bands together. 90

4. In an athletic protector, a rigid body defining a protective cup and having an integral flange extending upwards and laterally from the upper edge thereof, a soft rubber covering substantially completely enclosing said flange and covering the entire outer face of said cup and extending around the lateral and lower edges thereof, a belt adapted to encircle the wearer's waist 110 and secured at its forward portion to said protector, and leg bands each secured at one end to the back portion of said belt at one side thereof and at its other end to the lower portion of said cup. 115

5. In an athletic protector, a rigid body forming a cup, said cup being concave on its inner face considered both vertically and horizontally, the cup tapering from the top downwardly and terminating in a horizontal end at the bottom, 125 an integral flange in the upper portion of the cup, said flange being vertical and having a concave curve considered horizontally, the flange being in height relatively high compared with the height of the cup and in width extending laterally 130 beyond the upper portion of the cup, said cup at its front portion extending outwardly beyond the plane of the front portion of the flange, the cup and flange having a soft rubber covering secured thereto on the outside, such covering extending 135 on the inner face and upper edge of the flange and covering the marginal edges of the cup on the inside and outside, an abdominal belt connected to the inside cover of the flange, and straps secured to the belt and attached to the lower horizontal portion of the cup. 140

6. In an athletic protector, a rigid body structure having a lower portion formed as a cup structure concave on the inside considered both horizontally and vertically, said cup structure 145 being wider at the top and tapering downwardly and terminating at a horizontal lower end, the upper portion of the cup having an integral first flange connected thereto, the first flange being vertical and having a concave curvature con- 150

sidered horizontally, said first flange being wider than the upper portion of the cup, the marginal edges of the cup having a small integral second flange, the cup and first flange having a covering of sponge rubber on the outside, and the inside surface of the first flange having a sponge rubber covering, the small second flange on the margin of the cup being covered on the inside and outside with the sponge rubber, means to attach a belt to the first flange portion secured to the cup, straps depending from the belt, and a rivet connecting the straps to the lower horizontal end of the cup.

7. In an athletic protector, a rigid thin body structure having a lower portion formed as a cup structure concave on the inside both horizontally and vertically, said cup structure being wider at the top and tapering downwardly terminating at a small lower end, the upper portion of the cup

having an integral first flange formed on a concave curve on the inner side to conform to the abdomen of the wearer, said first flange being wider in a horizontal direction than the upper part of the cup to extend towards the sides of the abdomen of the wearer and such first flange having perforations, the marginal sides and lower edge of the cup having a second flange, a covering of sponge rubber on the outside and inside faces and upper and lateral edges of the first flange, the rubber extending through the said perforations between the inside and outside, the covering also being on the outside of the cup and on the second flange, a belt, means to attach the belt to the first flange, straps depending from the back of the belt, and means to secure the straps to the lower small end of the cup.
